ABSTRACT: A lamp socket structure for use with a threaded base lamp formed of a sheet of insulating material. The lamp socket structure is adapted to be mounted on a conductive plate defining one connection to the lamp base and the socket structure is provided with a contact defining the other connection to the lamp base. The sheet is provided with an opening defining means for threading the lamp thereto.

SOCKET STRUCTURE

BACKGROUND OF THE INVENTION

1. Field of the Invention

This invention relates to electrical devices and in particular to a lamp socket structure.

2. Description of the Prior Art

Many forms of lamp socket structures are provided for low-cost use such as in flashlights, toys, and games, wherein a low voltage such as obtained from flashlight batteries is employed. Such structures may comprise molded sockets and the like. One problem with such inexpensive socket structures is the ready loosening of the lamp bulb due to the relatively large tolerances involved in such low-cost moldings. Another problem is in the difficulty of mounting such sockets on flat sheets and the like such as where the sockets are used in connection with games. Another problem is in the relatively substantial cost of mold dies and the like where only a small number of such sockets are desired.

SUMMARY OF THE INVENTION

The present invention comprehends an improved lamp socket structure which may be formed of a flat sheet of plastic. The sheet may be suitably folded to define a pair of sheet portions biased toward each other to define a space into which the lamp base may be threaded. One of the sheet portions may carry a contact for engagement by the central terminal of the lamp base. The other of the sheet portions may be provided with a suitable hole through which the lamp base may be threaded.

Means may be provided for securing the lamp base to the underside of a metal plate having an opening in registration with the lamp base hole permitting the plate to serve as means for connection to the thread terminal of the lamp base.

The plastic sheet may be further provided with a cutout adjacent the threading hole to define means for frictionally retaining the lamp base in a threaded position in the socket structure. The sheet may be provided with suitable score lines for folding the sheet to define an end wall having edge portions adjacent the cutout defining the friction retaining means. The end wall may extend generally parallel to the direction of threading of the lamp base to the hole in the first sheet portion whereby the sheet portions are spaced the height of the end wall adjacent the lamp base and maybe secured together at the distal ends thereof to provide a resilient positioning of the sheet portions adjacent the end wall.

BRIEF DESCRIPTION OF THE DRAWING

Other features and advantages of the invention will be apparent from the following description taken in connection with the accompanying drawing wherein:

FIG. 1 is a top plan view of a sheet preform for forming the lamp socket structure of the invention;

FIG. 2 is an exploded view of the socket structure and lamp;

FIG. 3 is an end view of the socket structure; and

FIG. 4 is an enlarged vertical section of the socket structure and lamp as utilized in a game.

DESCRIPTION OF THE PREFERRED EMBODIMENT

In the exemplary embodiment of the invention as disclosed in the drawing, a socket structure generally designated 10 for use with a threaded base lamp generally designated 11 is shown to comprise a folded plastic sheet generally designated 12. The folded sheet may be secured to the underside of a metal plate 13 as by a rivet 14. The lamp may comprise a conventional low-voltage bulb having a base 16 and a filament 40.

As shown in FIG. 2, plate 13 may be provided with an opening 15 adapted to receive threaded base 16 of lamp 11 whereby plate 13 may comprise one connection to the lamp.

Folded sheet 12 may be formed of a flat sheet 17 of a suitable insulating material. Herein sheet 17 is formed of plastic, such as 0.03 inch linear polyethylene. Sheet 17 is provided

with a first score line 18 extending transversely across the midportion thereof and a second, broken score line defined by portions 19 and 20 defining therebetween an end wall portion 23. Sheet 17 further includes a keyhole slot 21 having a rectangular portion 22 extending into end wall portion 23, and a circular portion 24 in the left-hand sheet portion 25 as seen in FIG. 1. Sheet portion 25 is further provided with a rivet opening 26. The right-hand sheet portion 27 is provided with a corresponding rivet opening 28 and a contact rivet opening 29.

As best seen in FIG. 3, when sheet 17 is folded along the score lines, score line portions 19 and 20 define effectively parallel lines, with score line portion 19 intersecting slot portion 22 at a point closer to the bottom 30 of slot portion 22 than the intersection of score line portion 20 with the slot portion 22. Thus, the edge 31 of slot portion 24 is inclined downwardly, as seen in FIG. 3, at an angle preselected to correspond to the helix angle of the threaded lamp base 16 whereby the lamp base is effectively threadable in the edge 31.

As best seen in FIG. 1, circular slot portion 24 is cut short by rectangular portion 22 so that when the lamp base is threaded into portion 24, surface 32 of the lamp base frictionally engages end wall 23 adjacent slot portion 22 to retain the lamp in threaded association with the socket structure as best seen in FIG. 4.

Rivet 14 may be extended through the aligned openings 28 and 26 when the sheet is arranged in the folded disposition 12 of FIG. 2. Plate 13 is provided with a rivet opening 33 through which rivet 14 may be extended to secure the socket structure to the underside of the plate 13 with circular slot portion 24 aligned with plate opening 15 as best seen in FIG. 4.

A rivet 34 may be secured to sheet portion 27 in opening 29 with a looped wire end 35 secured between the rivet head and the sheet portion 27, as shown in FIG. 4, whereby rivet 34 may define the electrical contact for the central terminal 36 of lamp 11.

Illustratively, wire 37 may extend from looped end 35 thereof to a suitable battery, such as flashlight battery 38, and the other side of the battery may be connected to plate 13 to complete the electrical circuit to the lamp. In the illustrated embodiment of FIG. 4, the connection to plate 13 may be by means of a probe generally designated 39 which may be selectively engaged with the plate in accordance with a game provided on the upper surface so that the lamp will light whenever the probe engages the metallic plate 13. Obviously, other methods of completing the electrical circuitry may be utilized in conjunction with the socket device 10 within the scope of the invention.

When the lamp base 16 is threaded downwardly through opening 21 to engage rivet contact 34, the lower sheet portion 27 may be resiliently urged away from upper sheet portion 25 to provide a resiliently maintained contact of the lamp terminal 36 with the rivet 34 for improved electrical connection therebetween. This resilient action further tends to frictionally lock the lamp base in the socket, further consisting in maintaining the lamp against inadvertent loosening therein.

Hole 15 may be formed in metal plate 13 so as to have a friction fit with the lamp base by making the diameter of the opening only slightly smaller than the outer diameter of the lamp base whereby the threading of the lamp is effected solely into the socket opening 21 with the metal plate providing a friction-type electrical connection further serving to maintain the lamp against inadvertent unthreading in the assembly.

Thus, broadly, lamp socket structure 10 defines an improved means for mounting a threaded base lamp. The lamp structure may be formed of a sheet of inexpensive insulating plastic material provided with fold lines defining facially confronting portions joined by an end wall. In the illustrated embodiment, the fold lines are formed by score lines extending transversely across the sheet. An opening intersects one fold line and includes a first, segmentally circular portion in one portion of the sheet and a second portion in the end wall portion of the sheet. By forming the circular portion to have a

diameter substantially equal to the root diameter of the threaded lamp base, the lamp may be effectively threaded into the socket means with the side of the lamp base engaging the end wall of the socket structure to effectively frictionally retain the lamp threaded therein. Means are provided for maintaining the folded sheet in the folded arrangement so that the center terminal of the lamp base may have electrical connection to a contact mounted on another sheet portion resiliently disposed in spaced relationship to the first sheet portion. The means for retaining the sheet in the folded arrangement may further serve as means for securing the folded sheet structure to a metal plate defining a second electrical connection means engaging the side of the lamp base.

Thus, the lamp socket structure of the present invention is extremely simple and economical of construction while yet providing an improved lamp mounting wherein the lamp is effectively positively retained in the socket against vibration and the like while maintaining electrical connections to the lamp base.

The foregoing disclosure of specific embodiments is illustrative of the broad inventive concepts comprehended by the invention.

I claim:

1. Socket structure for use with a threaded base lamp comprising:

a sheet of insulating material having fold line means defining first and second sheet portions joined at said fold line means, and an opening intersecting said fold line means and having a first, segmentally circular portion in said first sheet portion and a second portion in said second sheet portion, said circular portion having a diameter substantially equal to the root diameter of a threaded lamp base; and

means for retaining said sheet portions in a folded arrangement wherein a lamp base may be threaded through said first opening portion to a preselected installed position wherein the outside surface of said threaded lamp base frictionally engages the portion of said second sheet portion defining said second opening portion to retain the lamp in the preselected installed position.

2. The socket structure of claim 1 wherein said sheet includes a third portion joined to said second sheet portion at a second fold line, said third sheet portion extending in facial confrontation to said first sheet portion.

3. The socket structure of claim 2 wherein said retaining means further secures said third portion in said facial confrontation to said first sheet portion.

4. The socket structure of claim 1 wherein the lamp includes a filament and means are provided on said sheet defining an electrical contact for engagement by an end portion of the lamp base to provide an electrical connection to one end of the lamp filament connected to said lamp base end portion.

5. The socket structure of claim 2 wherein the lamp includes a filament and means are provided on said sheet third portion defining an electrical contact for engagement by an end portion of the lamp base to provide an electrical connection to one end of the lamp filament connected to said lamp base end portion.

6. The socket structure of claim 1 wherein said fold line means includes longitudinally disaligned portions on opposite sides of said opening having opposed ends at said opening spaced apart substantially one-half the pitch of the lamp base

thread.

7. The socket structure of claim 1 wherein said second opening portion comprises a substantially straight-sided opening portion extending radially away from said first circular opening portion when said first and second sheet portions are disposed substantially in a common plane.

8. The socket structure of claim 1 wherein said second opening portion extends only partially the extent of said second sheet portion away from said first sheet portion.

9. The socket structure of claim 1 wherein said sheet is formed of a synthetic plastic.

10. The socket structure of claim 1 wherein said sheet is formed of polyethylene.

11. The socket structure of claim 1 wherein the lamp includes a filament and a metal plate is facially juxtaposed to said first sheet portion and is provided with an opening adapted to receive said threaded lamp base while providing an electrical contact with the thread thereof to define an electrical connection to an end of the lamp filament connected to the thread.

12. The socket structure of claim 1 wherein a metal plate is facially juxtaposed to said first sheet portion and retained in association therewith by said retaining means.

13. The socket structure of claim 1 wherein said sheet includes a third portion joined to said second sheet portion at a second fold line and extending in facial confrontation to said first sheet portion, said retaining means securing said third portion of the sheet in said facial confrontation to said first sheet portion and securing a metal lamp connector in association with said first sheet portion to be engaged by the threaded lamp base when the threaded lamp base is threaded into said opening.

14. Socket structure for use with an incandescent lamp having a base, comprising:

a sheet of insulating plastic having a first leg portion, a bight portion, and a second leg portion having an end portion spaced from the first leg portion by the bight portion and a securing portion spaced from said end portion, an opening in said first leg portion adapted to receive a lamp base, said leg portion defining distal ends;

means associated with said first leg portion for providing a first electrical connection to one connection portion of the lamp base; and

means associated with said second leg portion for providing a second electrical connection to another connection portion of the lamp base.

15. The socket structure of claim 14 wherein means are provided for securing the distal ends of said first and second leg portions in facial engagement, said sheet being formed of a resilient plastic, said means associated with said second leg portion for providing a second electrical connection being resiliently biased toward said first leg portion by the facial engagement of said distal leg ends.

16. The socket structure of claim 14 wherein means are provided on said bight portion of the sheet for frictionally engaging a lamp base installed through said opening on said first sheet leg portion to releasably retain a lamp in said socket structure.

17. The socket structure of claim 14 wherein said sheet portions are integrally joined.

18. The socket structure of claim 14 wherein said sheet portions are integrally joined by fold line means.
